UNITED STATES PATENT OFFICE.

CHARLES R. FARUOLO, OF NEW YORK, N. Y.

AUTOMOBILE-HEATER.

1,124,403.

Specification of Letters Patent. Patented Jan. 12, 1915.

Application filed October 17, 1913. Serial No. 795,628.

To all whom it may concern:

Be it known that I, CHARLES R. FARUOLO, a citizen of the United States, and a resident of the borough of Bronx, in the city, county, and State of New York, have invented certain new and useful Improvements in Automobile-Heaters, of which the following is a specification.

This invention relates to the heating of automobiles.

My objects have been to provide a thoroughly practical and efficient means for heating the interiors of such vehicles by use of the engine cooling water, to make the construction simple and inexpensive, compact and conformable, to keep down the added weight, to enable the invention to be installed neatly and conveniently in existing machines or embodied therein with advantage at the time of manufacture, and to provide a heating attachment of such character as to be readily adaptable to different conditions encountered in automobiles of various kinds. These and other advantages, which will be apparent to those skilled in the art, are attained by the novel features of constructions and combinations of parts hereinafter described and claimed.

An illustrative embodiment of the invention is shown in the accompanying drawings wherein:

Figure 1 is a side elevation showing the invention installed, the parts of the vehicle being represented somewhat conventionally and in the main by broken lines; Fig. 2 is a plan view of the heating radiator, its case being partly broken away; Fig. 3 is a section on the line 3—3 of Fig. 2; Fig. 4 is a section on the line 4—4 of Fig. 2; Fig. 5 is a detail enlarged view showing a part of the connections; Fig. 6 is a vertical section through the corresponding part of Fig. 5; Fig. 7 is a detail of a part shown in Figs. 5 and 6; and Fig. 8 is a detail illustrating the nature of the flexible pipe lines employed.

The drawing indicates a vehicle with a limousine body; but it will be understood that the invention is applicable to any type of car, open or closed. It is designed more particularly for heating the compartment or compartments pertaining to the rear seat or seats, which do not receive the benefit of the heat radiated by the engine. The latter is indicated in a conventional way at 10,

beneath the usual hood. The engine has the usual spaces for circulation of cooling water, hereinafter termed the water-jacket, and at the front of the hood is a usual or suitable form of radiator 11, through which the hot water from the water-jacket passes to dissipate its heat into the atmosphere, thence returning to the water-jacket again. The outlets from the water-jackets of the several cylinders are connected to a discharge manifold 12, and similarly their inlets are in communication with a return manifold 13. The discharge and return connections are tapped into the upper and lower portions of the radiator, and include flexible or hose sections 14, 15, by means of which injury to the joints by vibration is avoided. A pump 16 is interposed in the return connection and serves to maintain a circulation through the engine cooling system and also through the vehicle heating system.

The heating radiator is represented at 17, and is shown placed on the floor immediately in front of the rear seat. It is preferably constructed of a suitable number of parallel lengths of pipe connected by return bends; and the whole is preferably enclosed in a flat perforated metal case or box 18, the side and front edges of which are desirably beveled, as indicated at 19, to present a neat finish and avoid danger of the occupants tripping. The inlet and outlet of the radiator are preferably, though not necessarily, located at the same end, and as shown the inlet 20 passes through the front of the box while the outlet 21 drops downward through the bottom thereof. Obviously the details may be varied. The supply and return lines 22, 23 leading to said inlet and outlet, respectively, are connected with the hot and cold sides of the cooling system, by being tapped into the flexible hose sections 14, 15, and are light, flexible and anti-vibrating in character. To this end I construct them of spirally wound flexible metal tubing having at the rear ends suitable connections with the inlet and outlet of the radiator, and at their forward ends being provided with fittings 24, 25 for connection with said hose sections. This construction enables the heater to be connected conveniently and advantageously with the engine cooling system, and permits the supply and return lines to be disposed in any

manner preferred or that may be rendered desirable by the engine or car design or the presence of other parts or accessories, while merely by varying the length of the flexible lines the attachment is made applicable to any car. Furthermore, the total weight of the added parts is kept within a moderate limit, and the radiator 17 is effectively insulated from disagreeable transmitted vibration, as are all parts where leakage might develop, while rattling of the pipe lines, even though loosely laid, is avoided.

The tubing of the supply and return lines is provided internally with a continuous asbestos lining 26, the latter rendering the pipes water-tight, and, in the case of the supply line, being of further advantage in that it retains the heat. As indicated, the tubing may be inclosed, where desired, in a cover or envelop 27, which preferably has an asbestos packing 27' in the case of the supply line. As suggested in Fig. 8, the asbestos lining is desirably formed by employing a strip of asbestos of substantially the same width as the metal strip and winding it simultaneously therewith.

A suitable and preferred construction of the fittings 24, 25 is illustrated more particularly in Fig. 5. As here shown a flanged end piece 28 is soldered or otherwise secured to the end of the flexible pipe, a flanged nipple 29 is passed through an opening formed for the purpose in the wall of the hose section 14, and a union 30 draws the two together. The nipple 29 is held in place with a tight joint by a nut 31 screwed onto the nipple, a washer 32 being interposed between the nut and hose. A washer or part 33 having a similar function is interposed between the flange of the nipple 29 and the wall of the hose on the inside, and as shown in Fig. 6 is preferably curved transversely to conform to the curvature of the said wall. This member may be made of suitable extent and serves to reinforce the hose at the junction of the supply line therewith. It will be understood that the fitting or coupling 15 is of similar character, and that the details of construction may be varied in both instances.

Means are provided inside the discharge connection section 14 for causing a proper proportion of the hot water to flow into the inlet of the supply connection. To this end a member 34 is disposed across the interior of this hose section, the same being provided with an aperture 35 of suitable dimensions. Thus the passageway to the engine radiator is restricted, at a point beyond the inlet of the supply line, so that a portion of the flow is diverted into the latter. As shown the parts 33, 34 are advantageously formed as a single angular member, the passage-restricting member being thus anchored in place without the necessity for special means for

the purpose. It will be understood that the passage-restricting means need not be employed in the hose section 15.

The supply line 22 may be provided with a flexible branch 36, which is connected in a suitable manner with an outlet opening 37 near the top of the engine radiator, but preferably below the inlet opening 38. This branch connection may, however, be omitted, or in some instances, for example with the so-called siphon engine cooling system, it could be employed alone, without the connection with the hose section 14. When employed in conjunction with the other connection it insures an adequate supply of hot water to the heating radiator in the car without the necessity of very materially reducing the area of the connection 22.

As will be apparent, the heater may be applied with a minimum of labor and without any substantial alteration in the engine or vehicle. When in use part of the water passing from the engine water-jacket to the cooling radiator enters the supply line 22 and proceeds to and through the heating radiator, whence it passes through the return line 23 to the hose section 15, and, having given up its heat in the interior of the car, reunites with the cool water returning from the cooling radiator. Both then enter the intake of the pump, and are forced again through the cooling spaces of the engine. The two radiators are, thus, connected substantially in parallel.

The cooling radiator always remains in communication with the engine jacket; but the inside radiator may be cut off by means of valve fittings 39, 40 interposed in the supply and return lines near their forward ends. Couplings 41, 42 enable the major portions of these lines to be disconnected from the valve fittings when it is desired to remove the attachment from the vehicle. At such time the valves are, of course, closed. The valve of the fitting 40 in the return line is preferably a drain cock, as indicated. When this valve is open for through communication the drain is closed, but when closed to cut off the radiator 17, the vent is opened to permit the draining of the radiator. This valve also enables air to be vented in event of the radiator 17 becoming air-bound. The disposition of the supply and return lines is preferably such that the supply line is higher than the return, and the latter is preferably arranged with a continuous pitch from the outlet of the radiator 17 to the valve fitting 40. The radiator is also preferably arranged on a slight slant as indicated.

While I have described the illustrated embodiment of the invention with particularity so that the same may be fully understood, it will be apparent that I am not necessarily limited to the details shown, and that numerous changes, omissions and substitutions may

be made without departing from the invention.

What I claim as new is:

1. In an automobile, the combination with
5 the engine thereof provided with a water-jacket, a cooling radiator, and removable
flexible hose sections connecting the engine
water-jacket with the cooling radiator at top
and bottom, of a heater within the car, and
10 flexible supply and return lines leading to
and from said heater and connected, respectively,
to said hose sections.
2. In an automobile, the combination with
15 an engine water-jacket, an engine radiator,
and discharge and return connections between
said jacket and radiator, of a heating
radiator within the car, a supply line tapped
into said discharge connection and leading
20 to said heating radiator, means for securing
the inlet end of said supply line to said discharge
connection, and a member held in
place by said means within said discharge
connection and serving to restrict the
25 passage through the latter at a point beyond the
inlet of said line.
3. In an automobile, the combination with
an engine water-jacket, an engine radiator,

and discharge and return connections between
said jacket and radiator, of a radiator
within the car, a supply line leading thereto
from said discharge connection, a flanged
nipple projecting through the wall of said
discharge connection for attachment of said
line, and an angular member having an aper-
tured portion interposed between the flange
30 of said nipple and the wall of said discharge
connection and another apertured portion
disposed across the interior of said connec-
tion beyond said nipple so as to restrict the
passage through said connection. 40

4. In an automobile, the combination with
an engine water-jacket, an engine radiator,
and discharge and return connections between
said jacket and radiator, of a radiator
within the car, and a supply line leading
45 thereto from said discharge connection and
having a branch tapped into the upper por-
tion of the radiator.

In witness whereof I have signed my name
in the presence of two subscribing witnesses. 50
